HOBBYHORSE

Louis E. Reames, Lake Charles, La.

Application March 14, 1952, Serial No. 276,497

2 Claims. (CL. 272—52.5)

1

This invention relates to toys. More particularly, the invention has reference to a child's toy of the hobbyhorse type, readily formed in the simulation of an animal and having an up-and-down rocking motion when supporting a child.

One important object of the present invention is to provide a child's toy as stated, which is so designed as to be given its up-and-down motion by a novel means wherein the motion is maintained with the expenditure of a minimum amount of effort on the part of the supported child.

Another important object is to provide a toy as stated wherein a child-supporting body is formed in the simulation of an animal, and is pivotally mounted upon a stationary base, said body being so arranged relative to a balance wheel as to cause the weight of the child to be balanced against a counterweight marginally located in the wheel, thereby to produce a smooth up-and-down motion on the part of the pivoted body of the device.

Yet another important object is to provide a toy as stated wherein the mechanical means employed for producing the desired motion of the body is substantially concealed, and is located where it will be unable to injure the child.

Still another important object is to provide a toy of the character referred to in which the several desirable objects stated above will be met, while still keeping the construction simple, durable, and capable of manufacture at relatively low cost.

Other objects will appear from the following description, the claims appended thereto, and from the annexed drawing, in which like reference characters designate like parts throughout the several views, and wherein:

Figure 1 is a top view of a toy formed in accordance with the present invention;

Figure 2 is a longitudinal sectional view taken substantially on line 2—2 of Figure 1;

Figure 3 is a transverse sectional view taken substantially on line 3—3 of Figure 2; and

Figure 4 is an enlarged, detail sectional view taken substantially on line 4—4 of Figure 2.

The child-supporting toy formed in accordance with the present invention includes a stationary, supporting surface-engaging base designated generally by the reference numeral 10. The base, as well as practically all other components of the toy, can be readily manufactured from ordinary wooden stock, thus to simplify the construction and assembly of said components to a maximum extent.

2

The base 10 includes a flat support plate 12 adapted to be positioned against a supporting surface S such as a floor, the support plate 12 being of any desired outer configuration. In the present instance, as noted from Figure 1, the front end portion of the support plate 12 is tapered, and rounded, to add to the attractiveness of the completed toy. However, this particular appearance can be varied as desired.

10 Fixedly secured to the rear end portion of the base plate or support plate 12 are uprights 14, a pair of said uprights being provided. The uprights 14 are arranged vertically in parallel relation (Figure 3) and are spaced closely apart by 15 means of a spacer block 16 mounted upon the support plate 12 at the lower ends of the uprights.

The base also includes a pair of horizontally disposed support members 18, the front end portions of which are fixedly attached to the support plate 12 and, if desired, to the respective uprights 14.

20 The support members 18 project rearwardly from the support plate 12 a substantial distance, as may be readily noted from Figure 2, thus to elongate the base substantially, for a purpose to be made apparent.

The front end portions of the respective support members 18 are received in angular recesses 25 formed in the inner edges of upstanding stirrup members 22, said members 22 being fixedly secured at their lower ends to the support plate 12 and being arranged transversely of the support plate, in a common plane. At their upper 30 ends, the stirrup members 22 are cut away as at 35 24, to provide recesses adapted to receive the feet of a child supported upon the toy.

Mounted upon and between the uprights 14 is 40 a balance wheel 26 of substantial diameter, said wheel being rotatably mounted upon said uprights. The balance wheel 26, as will be readily noted from Figure 3 or Figure 4, is mounted upon a shaft 28, the wheel being fixed to the shaft for rotation therewith in any suitable manner.

The shaft 28 is journaled in bearings 30 provided in the respective uprights 14, and has its opposite ends projecting beyond the uprights in opposite directions. Fixed to said projecting ends of the shaft 28 are the inner ends of cranks 32, said cranks rotating with the balance wheel 26 and being pivotally connected at their outer ends to pitmans 34. The pitmans 34, in this connection, are pivotally connected at one end to the cranks 32, and at their other ends are pivotally connected to the opposite sides of an

animal-simulating body 36, by means of pins 38 or the like. Pin 38, the shaft 28, and stirrup recesses 24 all lie in a common vertical plane.

The balance wheel 26 is provided with a counterweight 40 at one location on its margin, and it is believed important to note, in this regard, that the crank 32 extends from the wheel center in a direction away from said counterweight.

If desired, inclined guides 42 can be secured to the opposite side plates 44 of the child-supporting body 36, to control the swinging movement of the pitmans 34.

The side plates 44 can be formed of any suitable material, such as plywood or the like, and are so shaped, so far as the outer configuration thereof is concerned, as to simulate the body of a selected animal. In the present instance, a horse has been illustrated, but it will be readily understood that any other animal simulation desired can be used, at the option of the manufacturer.

The side plates 44 are vertically arranged at opposite sides of the uprights 14, and are rigidly connected, in spaced, parallel relation by a horizontal top crosspiece 46, and inclined, rear and front end crosspieces 48, 50 respectively.

To complete the simulation of the animal, the body 36 is provided with a head 52 which in the present instance is formed in the simulation of the head of a horse, the body being also provided, at its rear end, with a tail 54. A saddle 56 is fixedly secured to the top crosspiece 46, intermediate the opposite ends thereof, so as to permit a child to be supported upon the body 36 at a location substantially medially disposed between the opposite ends of the body, and located above the balance wheel 26 and the pivotal connections 38 of the pitmans to the child-supporting body. The head 52, preferably, is provided with a handle 58 which can be grasped by the supported child.

Extending between and journaled in the rear ends of the support members 18 is a pivot shaft 60, said shaft extending through registering openings formed in the rear ends of the side plates 44 of the body 36, thus to pivotally connect said body to the base, for up-and-down swinging movement.

By reason of the construction illustrated and described, it will be seen that when a child's weight is supported upon the body 36, the up-and-down rocking motion of the body will be initiated, since the weight of the child will cause the balance wheel 26 to be rotated to a position in which the counterweight 40 is located at the upper limits of its travel. Thereafter, the child exerts a slight pressure against the stirrup members, to swing the body 36 upwardly once again, and the balance wheel will continue to rotate. Once the wheel is set in motion, it will tend to remain in motion, with a minimum amount of effort on the part of the child, and thus a smooth, easy, up-and-down movement of the animal-simulating body is obtained. It will be noted, in this regard, that the weight of the child tends to balance the counterweight 40, so as to reduce substantially the amount of effort to be expended by the child, and increase the smoothness of the rocking motion.

It is desired, in the preferred embodiment of the invention, to produce sounds simulating the hoofbeats of an animal, and to this end, I secure a plurality of lugs 62 to the periphery of the balance wheel 26. A block 64 is fixedly mounted upon the support plate 12 adjacent the periphery of the wheel, and embedded at one end in the

block is a flexible flap 66 of leather, rubber, or the like, the free end of said flap being disposed in the path of the circumferential series of lugs 62. As a result, when the wheel 26 rotates, the lugs 62 will strike the flap 66 in succession, causing slapping sounds simulating with considerable faithfulness the hoofbeats of a galloping animal.

As will be seen from Figure 3, the lugs 62 are spaced irregularly about the periphery of the wheel and are confined to approximately 180 degrees thereof. As a result, since the wheel rotates 360 degrees with each up-and-down cycle of the body, the hoofbeat-simulating sounds will be produced only during half of each body cycle. This adds considerably to the faithfulness of the simulation. In this connection, it will be seen that there are only three lugs 62, these being spaced irregularly about the periphery of the wheel in an arrangement which causes a single sound to be made, followed after a brief interval by two more sounds made in rapid succession. This sequence is quite close to that produced by the hoofbeats of a galloping horse.

Although the toy illustrated and described herein is shown as having a counterbalanced wheel, the counterbalance need not be necessarily placed in a circular member such as the wheel 26. Instead, it could be mounted upon the free end of an arm having its other end fixedly secured to the shaft 28. This modification is believed sufficiently obvious as not to require special illustration.

It is believed clear that the invention is not necessarily confined to the specific use or uses thereof described above, since it may be utilized for any purpose to which it may be suited. Nor is the invention to be necessarily limited to the specific construction illustrated and described, since such construction is only intended to be illustrative of the principles of operation and the means presently devised to carry out said principles, it being considered that the invention comprehends any minor changes in construction that may be permitted within the scope of the appended claims.

What is claimed is:

1. In a child's toy of the hobbyhorse type, a stationary, supporting surface-engaging, base, said base including a pair of spaced uprights disposed intermediate opposite ends thereof and a pair of upstanding, spaced, stirrup members rigid with said uprights and having recesses adapted to receive the feet of a child; a balance wheel mounted upon and between the uprights for rotation in a vertical plane, said wheel including a counterweight marginally located thereon; a crank secured to the wheel and extending from the wheel center in a direction away from the counterweight; a body pivotally connected at one end to one end of the base for swinging movement in a vertical plane and having its intermediate portion spaced vertically of and above the wheel and adapted for supporting a child; and a pitman connected at its opposite ends to said intermediate portion and crank respectively with its connection to the intermediate portion being spaced vertically of and above the center of rotation of the wheel, whereby to impart to the body, responsive to rotation of the wheel, an up-and-down rocking motion controlled by balancing of the counterweight against the weight of the supported child, said recesses of the stirrup members, the wheel center of rotation, and connection of the pitman to the intermediate por-

tion, all lying substantially in a common vertical plane.

2. In a child's toy of the hobbyhorse type, a stationary, supporting surface-engaging, base; a wheel mounted upon the base for rotation in a vertical plane; a crank secured to the wheel; a body formed in the simulation of an animal and pivotally connected at one end to the base for swinging movement in a vertical plane, said body having its intermediate portion disposed above the wheel and adapted for supporting a child; a pitman connected at its opposite ends to said intermediate portion and crank respectively, whereby to impart an up-and-down rocking motion to the body simultaneously with rotation of the wheel, said body moving through a single up-and-down cycle on each rotation of the wheel through 360°; a series of spaced lugs mounted upon the periphery of the wheel, said lugs being

spaced irregularly about said periphery and being confined within approximately 180° thereof; and a flexible flap mounted on the base, said flap being disposed in the path of said lugs so as to be struck thereby on rotation of the wheel, thus to produce audible sounds in rapid succession during half of each body cycle in simulation of an animal's hoofbeats, said lugs being confined substantially to that part of the wheel periphery moving past the flap during the downward movement of the body.
